CAN SHAKING DEVICE

Axel W. Anderson and Ralph Cover, Westminster,
Md., assignors to The United Company, West-
minster, Md., a corporation of Maryland

Application February 8, 1950, Serial No. 143,076

12 Claims. (CL. 259—54)

1

This invention relates to machines for shaking containers to mix their contents. Such shaking treatment is used in various food canning processes, and the invention will be described as embodied for this purpose.

The suggested process and the mechanical embodiment of the invention here chosen for illustration are exemplary, and no necessary limitation to a food process or to a specific machine is implied. Cans of paint and other products are sometimes shaken, and approximately cylindrical containers other than cans can be treated. Preferably, the cylindrical containers are reciprocated in the general direction of their longitudinal axes and the apparatus will be described as so used. When this type of shake is used the containers should approximate true cylinders closely enough to roll in a substantially straight line between guides, and in any case they should be substantially identical in form and size.

The machine can be set to receive containers of a considerable range of lengths and of a considerable range of diameters. The first commercial machine built would accept cans of 8 oz. capacity to number ten, and of any commercial length and diameter, and will shake number two cans, at the rate of 200 cans per minute.

Means are provided to vary the speed of shake between about 160 and 500 cycles per minute with an amplitude of 2½ inches. The amplitude is determined by the effective radius of the cranks. Adjustable radius cranks are known, but are not well adapted to withstand re-current shock. Hence, if change of amplitude ever be desired, it can best be effected by interchanging cranks of different radius. As a practical matter no condition requiring change of amplitude has been encountered.

Change of duration of treatment is effected by changing between 25 and 70 feet per minute the lineal travel of the conveyor belt.

All the figures above given are illustrative. They are values found practicable and satisfactory over a useful range of conditions.

A preferred embodiment of the invention will now be described by reference to the accompanying drawings, in which:

Fig. 1 is a perspective view from near the feed end, looking toward the right hand side of the machine, and shows all except the extreme discharge end of the machine.

Fig. 2 is a vertical axial section of the feed end, showing the flight conveyor and the flexible side guides which engage the ends of the cans.

Fig. 3 is a plan view of the parts shown in Fig. 2.

Fig. 4 is a plan view, largely diagrammatic, showing the conveyor belt, the side guides, the shaking trough and the means for tensioning the side guides.

Fig. 5 is a detail plan of the articulated floor plate which supports the conveyor belt as the latter approaches, passes through and leaves the shaking trough.

Fig. 6 is a bottom view and Fig. 7 an axial section through one of the joints shown in Fig. 5 and drawn on a scale larger than that of Fig. 5.

Fig. 8 is a detail of the conveyor drive.

Fig. 9 is a fragmentary side elevation of the discharge end portion of the machine (a portion only partly visible in Fig. 1).

Fig. 10 is a transverse section through the machine, taken at the entrance to the shaking section and looking toward the discharge end, and

Fig. 11 is a detail of one of the conveyor flights showing the protective envelope.

Refer first to Figs. 1 to 4 inclusive. Since substantial inertia effects are developed, the machine requires a rigid and massive frame. The main frame members are sills 15 and cross frames 16 constructed of I-beams welded together. Mounted on the I-beams at opposite ends of the base frame are two similar frame structures 17 (best shown in Fig. 1) and 18 (best shown in Fig. 9). These frames are sustained laterally by diagonal braces 19 and are sustained longitudinally by diagonal braces 21. The form of the frames 17 and 18 is subject to considerable possible variation, provided adequate strength is afforded. Consequently, the details of the frame are not elaborated.

Between the two end frames 17 and 18 and supported directly on the sills 15 are two heavy frames 22 and 23 which carry the bearings 24 for two horizontal rocker shafts 25 which are parallel with the longitudinal sills 15. The two frames 22 and 23 are braced together by the channel member 26 and are connected with the end frames 17 or 18, as the case may be, by angle iron braces 27. Each shaft 25 carries fixed to it a pair of parallel rocker levers 28. These are the levers which carry the shaking trough. At mid-stroke all four of the levers 28 are vertical. They are connected together in pairs at their lower ends by massive links 29 which not only connect the rocker levers 28 for parallel motion, but also serve as counterweights for the shaker trough structure. The purpose is to balance as

closely as is reasonably practicable the oscillating masses in the machine.

Each of the combined counterweight and link members 29 is connected to the two sill members 15 by two coil tension springs 31. These are selectively stressed as the members 29 move in reverse directions from their mid-position. The springs 31 perform a very useful function in smoothing the action of the machine, particularly at the moment of reversal of motion. The link members 29 are driven from a shaft 32 by cranks 33 each through a pitman 34. The cranks 33 are parallel and of equal radius so that the members 29 are reciprocated in phase with each other and with the same amplitude.

The shaft 32 is driven by a motor 35 through a variable ratio speed-reducing train of conventional form enclosed in the housing 36. As best shown in Fig. 10 the drive is from the motor 35 through a sprocket chain and pinion generally indicated at 37 to the speed-reducing mechanism in the housing 36, and from that mechanism through another sprocket chain drive 38 to the shaft 32. In a commercial machine which has operated successfully the motor 35 is a constant speed electric motor and the variable speed reducer can be set to drive the shaft 32 at selected speeds from 160 revolutions to 500 revolutions per minute. The details of the speed-reducing mechanism are not illustrated as the device indicated at 33 is a standard commercial device.

The cranks 33 in the machine above mentioned have a radius such that the knuckle pins 39 at the upper ends of the four rocker levers 28 have an amplitude of approximately 2½ inches when the shaft 32 is rotated. The pins 39 connect the levers 28 and bearing brackets 41 on two U-shaped frames 42 and 43 which support and are a part of the guiding frame which imparts a shaking motion to the cans. This frame also comprises four longitudinal angle pieces 44, two rectangular end frames 45 welded to the ends of the longitudinals 44 and a number of diagonal braces 46 so located as to stiffen the frame and render it adequate for the duty which it has to perform.

Adjacent the brackets 42 and 43 on both sides of the frame are two cross members 47 in which are adjustably mounted two support rods 48. These rods may be locked in adjusted position by clamping means indicated at 49 and carry bosses 51 to which the trough forming side plates 52 are connected.

The members 48, 49 and 51 are the means by which the plates 52 can be adjusted toward and from each other to define different widths of guide trough for the cans.

Supported by the members 42 and 45 is the floor member 53 of the trough. This is best shown in Figs. 1, 5 and 10. It takes the form of an elongated steel plate welded to the shaking frame at the center and flexibly connected at its ends to an approach floor section 54 and a discharge floor section 55.

At their remote ends the sections 54 and 55 are hinged to brackets supported by the corresponding end frame. Such hinged support for the member 53 is clearly shown at 56 in Fig. 2. The joints between 53 on the one hand and 54 and 55 on the other are clearly illustrated in Figs. 6 and 7. At the ends of the member 53 stirrups 57 are welded to its lower face. The stirrups receive tongues 58 welded to the lower face of the member 54 or 55 as the case may be. The ends of the tongues 58 are tapered and work

freely, so far as lateral motion is concerned, in the corresponding stirrups 57. To prevent excessively free motion, small bolts 59 extend through the member 53 and the stirrup 57 and are set up sufficiently to afford moderate frictional resistance to motion. The purpose served by the bolts 59 is chiefly the reduction of noise.

Plates 52 are connected to corresponding flexible side-guides 61 which desirably are formed of heavy canvas belting. The connection is made by bolts whose heads are countersunk in the belting. Some of the bolts appear at 62 in Fig. 10. The flexible side-guides 61 are approximately coextensive with the floor members 54, 53, 55 and are sustained by cylindrical support-members 63, best shown in Fig. 4.

These support-members 63 are journaled in four yokes 64 which are hinged to portions of the end frames 17 or 18 as the case may be. Since the members 61 are fixed to the members 52, tension means must be applied to both ends of the members 61. Thus, four tension members are used and take the form of rods 65 tensioned by coil compression springs 66 which can be adjustably stressed by turning the hand nuts 67 threaded on the end of each rod 65.

The tension in the member 61 tends to urge the supporting members 63 outward, i. e. away from each other. Consequently, they can be satisfactorily positioned by thrust screws 68, as best shown in Fig. 3. Since the length of the members 61 is several feet, and since their lateral motion at mid-length is only 2½ inches, the motion of the tension rods 65 is slight, and indeed almost imperceptible.

To feed a series of cans into, through and out of the shaking section of the machine, use is made of a flexible belt 71 carrying spaced flights 72. The belt 71 is narrower than the narrowest adjusted interval between the members 61. The flights 72 do not extend quite the full width of the belt. They are protected by rubber sleeves 73 which, as best indicated in Fig. 11, take the form of short sections of rubber tube stretched over the flights.

At the entrance end of the machine the belt 71 is supported on a cylindrical pulley 74. This is mounted on a shaft 75 driven through a sprocket chain 76 by a variable speed motor drive generally indicated at 77. This drive is also a commercial mechanism and in the machine above referred to drives the belt at lineal speeds which can be adjusted between 18 and 70 feet per minute. The belt 71 is endless and its discharge end is supported by a pulley 78 mounted in guides 79 and adjustable to tension the belt by conventional thrust screws 81.

Cans are fed to the belt 71 down two guide angles 82 whose horizontal spacing is adjustable. The adjusting means is best shown in Figs. 2 and 3 and comprises split clamps 83 engaging the horizontal rods 84. The rods 84 are in turn supported by triangular frames clearly shown in Fig. 1. The guide angles 82 are also adjustable in a longitudinal direction by the slot and bolt arrangement indicated at 85.

Cans placed on the guides roll by gravity to the conveyor. At the discharge end, similar downwardly inclined guides 86 receive the cans from the conveyor. The guides 86 are essentially similar to the guides 82 and are similarly adjustable.

Operation

As will be apparent from an inspection of Fig. 2, the size and spacing of flights 72 is such

as to afford considerable latitude as to can diameter. Cans of very large diameter can be handled by substituting a belt carrying higher and more widely spaced flights. Belt changing is rarely required.

Usually the first necessary adjustment is to space the plates 52 (and the attached flexible guides 61) to accept the desired length of can. This can be done conveniently by successively loosening each clamp 49, inserting a suitably dimensioned block gauge between member 47 and the adjacent boss 51, and with the gauge filling the interval, resetting the clamp. This assures correct alignment and is a quick and simple operation. The feed and discharge angles 82 and 86 can be spaced by trial with a can and can be centered by eye.

The rate of belt travel can be adjusted at any time (even while the machine is running) by moving the control element of the commercial speed reducer 77 in the ordinary manner.

The frequency of shake can be adjusted at any time (even while the machine is running) by moving the control element of the adjustable speed reducer 36 in the ordinary manner.

With all adjustments made, and the machine running, cans are fed to the guides 82 by any suitable conveyor, or manually. They are spaced by the flights on the conveyor belt and as they approach the shaking trough begin to shake, the amplitude of shake increasing until the full range is attained when they enter the trough. This amplitude continues until they reach the discharge end of the trough whereupon the amplitude of shake gradually diminishes.

The cans roll down guides 86 to an appropriate conveyor or other machine as circumstances dictate.

Economic conditions demand the use of light gauge tin plate, and lock seams for many cans. Such cans are relatively weak and susceptible to mechanical injury ranging from impaired appearance to leaky seams. The invention handles the cans by cushioned surfaces throughout the entire zone where any shaking occurs. As a consequence it is possible to use a greater amplitude and a higher frequency than has heretofore been used commercially, and to do so despite the relatively weak construction of present day cans.

Unlike prior art shakers the cans are never so handled that they tend to stack. Since each can is individually supported at all times, the risk of mechanical injury is minimized.

The machine subjects the cans to a violent shaking treatment, without marking any can and without damage to seams.

Limitations to the specific structure above described, or any detail thereof is not implied, the scope of the invention being defined solely by the claims.

We claim:

1. In a machine for shaking cans the combination of a supporting frame; rocking levers supported thereby; a can guiding member supported by said levers, forming therewith a parallel bar linkage, and arranged to guide cans in a direction normal to the planes in which said levers oscillate said member having a floor and two sides spaced to afford a trough-like passageway for a succession of cans; approach and discharge floor sections hingedly connected at one end with said frame, and at the other end, each with a corresponding end of said floor; flexible guide strips connected to the inner faces of said sides and extending substantially throughout the

aggregate length of said floor and the approach and discharge floor sections, said strips being supported at each end on said supporting frame and extending freely from the point of such support to respective ends of said can-guiding member; a conveyor belt narrower than said trough supported by said floor and floor sections and having can feeding flights; pulley means sustained by said supporting frame for tensioning and guiding said conveyor belt; means for oscillating said levers; and means for driving said conveyor belt.

2. The combination defined in claim 1 in which the flexible guide strips are of a fabric having a cushioning characteristic, and cushioning envelopes are mounted on said flights.

3. In a machine for shaking cans the combination of a supporting frame; rocking levers supported thereby; a can guiding member supported by said levers, forming therewith a parallel bar linkage, and arranged to guide cans in a direction normal to the planes in which said levers oscillate said member having a floor and two sides spaced to afford a trough-like passageway for a succession of cans; approach and discharge floor sections hingedly connected at one end with said frame, and at the other end, each with a corresponding end of said floor; flexible guide strips connected to the inner faces of said sides and extending substantially throughout the aggregate length of said floor and the approach and discharge floor sections, said strips being supported at each end on said supporting frame and extending freely from the point of such support to respective ends of said can-guiding member; a conveyor belt narrower than said trough supported by said floor and floor sections and having can feeding flights; pulley means sustained by said supporting frame for tensioning and guiding said conveyor belt; means for oscillating said levers; and means for driving said conveyor belt.

4. In a machine for shaking cans the combination of a supporting frame; rocking levers supported thereby; a can guiding member supported by said levers and arranged to guide cans in a direction normal to the planes in which said levers oscillate said member having a floor and two sides spaced to afford a trough-like passageway for a succession of cans; means affording adjustment of the interval between said sides; approach and discharge floor sections hingedly connected at one end with said frame, and at the other end, each with a corresponding end of said floor; flexible guide strips connected to the inner faces of said sides and extending substantially throughout the aggregate length of said floor and the approach and discharge floor sections, said strips being supported at each end on said supporting frame and extending freely from the point of such support to respective ends of said can-guiding member; a conveyor belt narrower than said trough supported by said floor and floor sections and having can feeding flights; pulley means sustained by said supporting frame for tensioning and guiding said conveyor belt; means for oscillating said levers; and means for driving said conveyor belt.

5. In a machine for shaking cans the combination of a supporting frame; rocking levers supported thereby; a can guiding member supported by said levers, forming therewith a parallel bar linkage, and arranged to guide cans

in a direction normal to the planes in which said levers oscillate said member having a floor and two sides spaced to afford a trough-like passageway for a succession of cans; approach and discharge floor sections hingedly connected at one end with said frame, and at the other end, each with a corresponding end of said floor; flexible guide strips connected to the inner faces of said sides and extending substantially throughout the aggregate length of said floor and the approach and discharge floor sections, said strips being supported at each end on said supporting frame and extending freely from the point of such support to respective ends of said can-guiding member; independent tensioning means reacting on respective opposite ends of said guide strips; a conveyor belt narrower than said trough supported by said floor and floor sections and having can feeding flights; pulley means sustained by said supporting frame for tensioning and guiding said conveyor belt; means for oscillating said levers; and means for driving said conveyor belt.

6. In a machine for shaking cans the combination of a supporting frame; rocking levers supported thereby; a can guiding member supported by said levers and arranged to guide cans in a direction normal to the planes in which said levers oscillate said member having a floor and two sides spaced to afford a trough-like passageway for a succession of cans; approach and discharge floor sections hingedly connected at one end with said frame, and at the other end, each with a corresponding end of said floor; flexible guide strips connected to the inner faces of said sides and extending substantially throughout the aggregate length of said floor and the approach and discharge floor sections; guide rollers engaging the end portions of said flexible guide strips; means for adjusting said rollers in directions transverse to said approach and discharge sections respectively; elastic tensioning means arranged to draw the end portions of said strips around said rollers; a conveyor belt narrower than said trough supported by said floor and floor sections and having can feeding flights; means for oscillating said levers; and means for driving said conveyor belt.

7. In a machine for shaking cans the combination of a supporting frame; rocking levers supported thereby; a can guiding member supported by said levers and arranged to guide cans in a direction normal to the planes in which said levers oscillate said member having a floor and two sides spaced to afford a trough-like passageway for a succession of cans; approach and discharge floor sections hingedly connected at one end with said frame, and at the other end, each with a corresponding end of said floor; flexible guide strips connected to the inner faces of said sides and extending substantially throughout the aggregate length of said floor and the approach and discharge floor sections; guide rollers engaging the end portions of said flexible guide strips; means for adjusting said rollers in directions transverse to said approach and discharge sections respectively; elastic tensioning means arranged to draw the end portions of said strips around said rollers; means for adjusting the stress exerted by said tensioning means; a conveyor belt narrower than said trough supported by said floor and floor sections and having can feeding flights; means for oscillating said levers; and means for driving said conveyor belt.

8. In a machine for shaking cans the combination of a supporting frame; rocking levers sup-

ported thereby; a can guiding member supported by said levers and arranged to guide cans in a direction normal to the planes in which said levers oscillate said member having a floor and two sides spaced to afford a trough-like passageway for a succession of cans; approach and discharge floor sections hingedly connected at one end with said frame, and at the other end, each with a corresponding end of said floor; flexible guide strips connected to the inner faces of said sides and extending substantially throughout the aggregate length of said floor and the approach and discharge floor sections said strips being supported at each end on said supporting frame and extending freely from the point of such support to respective ends of said can-guiding member; a conveyor belt narrower than said trough supported by said floor and floor sections and having can feeding flights; means for oscillating said levers; pulley means sustained by said supporting frame for tensioning and guiding said conveyor belt; means for driving said conveyor belt; and means for varying the speed of operation of said driving means.

25 9. In a can shaking device the combination of means forming an approximately horizontal can-way adapted to receive cans and guide them in a longitudinal traverse of the can-way, said means comprising a laterally flexible floor made up of articulated sections and sides spaced apart a distance approximating the corresponding dimension of the cans to be shaken, each side being formed of a continuous flexible strip adapted to resist substantial tensile stress; fixed supports at 30 respective ends of said can-way; means carried by said supports and serving to stress said strips in tension; hinged connections between said supports and the terminal portions of said floor; a horizontal reciprocable frame engaging and supporting the mid-portion of said can-way; a conveyor belt extending over the floor of said can-way in contact therewith and having upstanding flights adapted to engage individual cans and propel them while spaced apart in continuous series along said can-way; pulley means for tensioning and driving said belt; a fixed support for said pulley means; and independent connections for driving said pulley means and for reciprocating said frame.

50 10. The combination defined in claim 9 in which the flexible strips which form the sides of the can-way comprise a flexible fabric material and each is attached approximately at its mid-length to said reciprocable frame.

55 11. In a can shaking device the combination of means forming an approximately horizontal can-way adapted to receive cans and guide them in a longitudinal traverse of the can-way, said means comprising a laterally flexible floor made up of articulated sections and sides spaced apart a distance approximating the corresponding dimension of the cans to be shaken, each side being formed of a continuous flexible strip adapted to resist substantial tensile stress; fixed supports at 60 respective ends of said can-way; means carried by said supports and serving to stress said strips in tension; hinged connections between said supports and the terminal portions of said floor; a horizontal reciprocable frame engaging and supporting the mid-portion of said can-way; a conveyor belt extending over the floor of said can-way in contact therewith and having upstanding flights adapted to engage individual cans and propel them while spaced apart in continuous series along said can-way; pulley means 65 for

for tensioning and driving said belt; a fixed support for said pulley means; a manually adjustable variable speed drive for said pulley means; and a manually adjustable variable speed drive for reciprocating said reciprocable frame.

12. In a can shaking device the combination of means forming an approximately horizontal can-way adapted to receive cans and guide them in a longitudinal traverse of the can-way, said means comprising a laterally flexible floor and laterally flexible sides spaced apart a distance approximating the corresponding dimension of the cans to be shaken; said floor comprising at least three sections and hinge connections between said sections each including a tongue on one section, a stirrup in the adjacent section embracing said tongue and means for flexing the stirrup into frictional engagement with the related tongue; fixed supports for respective ends of said can-way; a horizontally reciprocable frame engaging and supporting the mid-portion of said can-way; a conveyor belt extending over the floor of said can-way in contact therewith

10

5 and having upstanding flights adapted to engage individual cans and propel them while spaced apart in continuous series along said can-way; pulley means for tensioning and driving said belt; a fixed support for said pulley means; and independent connections for driving said pulley means and for reciprocating said frame.
